UNITED STATES PATENT OFFICE.

CHARLES P. EISENHAUER, OF DAYTON, OHIO, ASSIGNOR TO THE DURG COMPANY, OF DAYTON, OHIO, A CORPORATION OF OHIO.

WATER SOFTENER.

Application filed October 12, 1925. Serial No. 61,997.

It is the object of my invention to provide an automatic water softener controlled by a meter which in turn controls a mechanical needle valve which controls the application of hydrostatic pressure to a brine valve and a refill valve and to a hydrostatic pressure operated mechanism which in turn mechanically operates a rotary valve for converting the system from softening to regenerating position, and vice versa.

Referring to the drawings:

Figure 1 is a front elevation, partially in section and with the cover removed from the casing of the meter and the control mechanism;

Figure 2 is a horizontal section through the master control valve for converting the parts from softening to regenerating position;

Figure 3 is a section on the line 3—3 of Figure 2, showing the valve in softening position;

Figure 4 is a similar view showing the valve in regenerating position;

Figure 5 is a front elevation of the complete assembled machine with the master hydraulic valve in section;

Figure 6 is an end elevation of Figure 1;

Figure 7 is a section through the unit consisting of the refill valve and brine valve.

Referring to the drawings in detail, 1 is a tank having a screen at either end and softening material therebetween with a pipe leading to the top and bottom of the tank in the conventional manner. In this system of softening water the main feed pipe of hard water is designated 2. The water passes by and through a screen 3 (Figure 1) carried on a screw plug 4 located within a screen chamber 5 which communicates with the chamber 6 of the meter. 7 designates the meter mechanism which operates the gears 8, 9, 10, 11, 12 and 13. This mechanism is located within the meter casing 14. The exit for the water is through the pipe 15 forming a meter line.

The gear 13 rotates the shaft 16 which in turn carries a heavier shaft 17 having mounted thereon a driving member 18 fixed in position on the shaft 17 by the set screw 19. The upper end of this shaft is carried in a bracket 20 forming a part of the driving mechanism casing 21. Also journalled in this bracket at right angles to the shaft 17 is a transverse shaft 22 which is supported

at one end in the side wall of the casing 21 as at 23. It is spring pressed towards the right hand by the spring 24 operating on the ball 25 which impinges upon the end of the shaft 22. On this shaft 22 is a driven disc 26 held in position by a cotter pin 27.

The free end of the shaft carries a worm wheel 28 engaging with the gear 29 carried on a shaft 30. On this shaft 30 is a cam 31 and a second cam link 32 supported adjacent thereto on an eccentric plate 33 mounted on the shaft 30. The plate and cam link are held together by the set screws 34. A cam follower 35 rides on this cam, such follower being a bell crank having an arm 36 pivoted on the frame 21 at 37 and having a second arm 38 with a head 39 engaging with a similar head 40 on the arm of a second bell crank 41. This second arm 41 is connected to the casing 21 by a spring 42. It is pivoted on a bracket of this casing at 43. The other arm of this second bell crank is designated 44 and has pivotally connected to it a supporting link 45 in which is supported, by a nut 46, a master control needle valve stem 47 which carries a ball 48 at the bottom thereof. This ball 48 is adapted to control a passageway 49 leading from the meter chamber to passageways 50 and 51. These passageways communicate with the pipes 52 and 53 leading respectively to the master control valve 54 and the brine and refill valves, generally designated 55 and 56.

The hydrostatic pressure on the line 52 will operate upon the diaphragm 57, thus actuating the valve member 58 which is in fact a plunger projecting outside of the valve casing 59 and terminating in an eye 60 which is pivoted at 61 to the lever 62. This lever is pivoted at 63. It carries at 64 its other end a pin 64 which rides in a jaw 65 of a lever 66 which in turn rotates a shaft 67 in the rotary valve casing 68. This rotary valve casing 68 contains a hollow valve member consisting of a cylindrical casing 69 having a chamber 70 therein. This chamber 70 has a port 71 and a port 85 at right angles thereto. This port 71 in Figure 2 is adapted to register with port 73 in the casing 68 which port is connected to the incoming city water from the meter line 15. The port 85 in Figure 2 is connected with the port 74 in the casing 68 which has in it ejector mechanism 75 projecting into a pipe 76 at right angles to a

communicating pipe 77. The pipe 76 leads to the top of the tank while the pipe 77 is the brine line.

Referring to the arrangement of parts in Figure 3 it will be noted that the incoming hard water through the line 15 and port 73, will pass into the passageway 78 formed by the parts 79 in the valve casing 69 and thence pass out through the port 80 in the casing 10 68 to the pipe 81 leading to the bottom of the softener.

In the position shown in Figure 4, the parts are so turned that the water will come upwardly through the pipe 81, and port 80 15 into the passageway 78, thence out through the port 82 and pipe 83 to the drain, which is the way the water is relieved from the bottom of the tank during regeneration.

In the construction shown in Figure 4 the 20 port 73 registers with the port 84 so that the water passes into the opening 85 and thence downwardly into the tank, as 85 is connected with the top of the tank and also bypasses through the line 86 to service 25 through the port 87 and port 88.

In Figure 3 during softening, the port 85 is the exit port through which the water makes its exit thence through the opening 89, port 88, and pipe 86 to service.

30 The hydrostatic line 53 passes to the hydrostatic chamber 90 above the diaphragm 91 of the refill valve. The pressure then passes through the passageway 92, through the screen 93, passageway 94 and by the ball 35 valve 95 into the passageway 96 to the brine diaphragm chamber 97 and thence through a screen 98 and bleed opening 99 to the pipe 100 where the surplus hydrostatic fluid passes into the brine tank.

40 The refill valve 55 has a plate 101 carried on its stem 102 beneath the diaphragm 91. It carries a collar 103 against which impinges a spring 104 resting on a shoulder 105 which moves the valve in one direction.

45 This valve stem 102 is projected into a partition 106 in the casing 107 separating the casing into two compartments 108 and 109. The partition has a valve seat 110 closed by a valve member 111 carried on the valve stem 50 102. The passageway 109 is blocked at its other end by a partition 112 having a valve seat 113 closed by a valve member 114. This controls communication with the chamber 115 which leads to the brine pipe 116 which in turn is connected with the brine tank 117.

55 The valve member 114 is supported by a valve stem 118 which is spring pressed in one direction by a spring 119 carried on the shoulder 120 and resting at its other end against the plate 121 carried by the valve stem 118. On this valve stem is a plate 122 adapted to engage with the brine valve diaphragm 123.

60 The refill valve is locked by the reciprocating plunger 124 which is pressed in one

direction by a spring 125 and moved in the reverse direction by one arm of the bell crank 126 which is pivoted at 127 and has its other arm 128 carrying a cross pin 129. This cross pin is carried between a pair of 70 jaws 130 between which project the jaws of the link 131 so that the pin 129 rests in a slot between such jaws. At the other end the link 131 is pivoted at 132 to a lever 133 supported in its free end by a spring 134 75 and at its other end by jaws 135 resting on a pin 136 carried on the casing of the brine valve. Between the link and the pivotal support of the lever 133 there is pivotally attached the needle valve stem 136^a which 80 actuates the ball 95 of the ball valve.

The float arm 137 having the float 138 is connected to the bell crank 126 so that the movement of the bell crank with the float 85 and float arm will serve to control the ball valve and the refill valve lock.

The brine line 116 passes from the bottom of the brine tank 117 and terminates in a bell 139.

Method of operation.

90

As the water passes through the system the meter 7 drives the driven disc 26 which in turn rotates the cam 32 so that when the high point of the cam is reached, it will 95 actuate the series of bell cranks 36, 38, 41 and 44 and open the needle valve 48, admitting hydrostatic pressure to the hydrostatically operated mechanism so that the master control rotary valve will rotate from the position shown in Figure 3 to the position shown in Figure 4 and Figure 2. Simultaneously, the pressure applied to the line 53 leading to the refill valve 55 and brine valve 56 will result in the opening 100 of the refill valve 55 and the locking of it open. It is closed during softening. The brine valve 56 is normally opened during softening and remains open, allowing the brine to be drawn through the brine line 116 to the top of the tank 117 and thence downwardly back to the master rotary valve 68 and out to the drain. This continues until the float 138 drops down to a predetermined point due to the removal of brine, whereupon the float arm moves the link 131 downwardly, actuates the lever 133 and opens the ball valve 94, allowing the hydrostatic pressure to close the brine valve 56, shutting off the brine. As soon as the system is 110 reversed to softening the brine valve 56 opens and the water passes to service through pipe 86 and also passes partially to one side back to the brine tank 117 to replenish it until the float 138 rises with the float arm 137, holding the locking plunger 124, allowing the refill valve 55 to close, thus shutting off further water being delivered to the brine tank 117. When this takes place the spring 125

115 member 114 is pressed in one direction by a spring 119 carried on the shoulder 120 and resting at its other end against the plate 121 carried by the valve stem 118. On this valve stem is a plate 122 adapted to engage with the brine valve diaphragm 123. The refill valve is locked by the reciprocating plunger 124 which is pressed in one 120 direction by a spring 125 and moved in the reverse direction by one arm of the bell crank 126 which is pivoted at 127 and has its other arm 128 carrying a cross pin 129. This cross pin is carried between a pair of jaws 130 between which project the jaws of the link 131 so that the pin 129 rests in a slot between such jaws. At the other end the link 131 is pivoted at 132 to a lever 133 supported in its free end by a spring 134 and at its other end by jaws 135 resting on a pin 136 carried on the casing of the brine valve. Between the link and the pivotal support of the lever 133 there is pivotally attached the needle valve stem 136^a which actuates the ball 95 of the ball valve.

125

130

for the rotary valve 68, upon the cessation of regeneration, moves the valve 68 back to a softening position.

It will be understood that I desire to comprehend within my invention such modifications as may be necessary to adapt it to varying conditions and changes, and by brine I mean regenerating material.

Having thus fully described my invention, what I claim as new and desire to secure by Letters Patent, is:—

1. In a water softening apparatus, means for controlling the operation thereof depending upon the quantity of water passing therethrough, valve means controlled thereby adapted to change the direction of water passing through the softener and to apply brine to the softening material therein, and to by-pass a portion of the hard water direct to service.

2. In a water softening apparatus, means controlled by the passage of a given quantity of water for converting the apparatus from softening to regenerating position, and back to softening position, a needle valve controlled thereby adapted to admit hydrostatic pressure to a hydrostatically operated mechanism, a hydrostatically operated mechanism, and means operated thereby for converting the softener from softening operation to regenerating operation, and vice versa.

3. In a water softening apparatus, means controlled by the passage of a given quantity of water for converting the apparatus from softening to regenerating position, and back to softening position, a needle valve controlled thereby adapted to admit hydrostatic pressure to a hydrostatically operated mechanism, a hydrostatically operated mechanism, and means operated thereby for converting the softener from softening operation to regenerating operation, and vice versa, a brine supply, and means for connecting said brine supply so controlled through a softening apparatus for regeneration, and means so controlled for diverting a part of the incoming water direct to service during regeneration.

4. In a water softening apparatus, means controlled by the passage of water therethrough for determining the alternate periods of softening and regeneration, hydrostatic means controlled thereby adapted to operate a rotary valve for changing the direction of water through the softener and for applying brine to the softening material in the softener, a rotary valve, a source of brine supply and means to regulate the amount of brine so supplied and the amount of water returned to the brine tank to replenish it.

5. In a water softening apparatus, means controlled by the passage of water for operating a needle valve at predetermined intervals, hydrostatic pressure adapted to be ad-

mitted by said needle valve to a plurality of hydrostatic valves and to a hydrostatically operated mechanism to operate a rotary valve for converting the softener from softening to regenerating position and back to softening position, said hydrostatic valve being adapted to control the refill and brine valves, a rotary valve adapted in one position to deliver hard water to one end of the tank and remove it softened from the other end of the tank, and in the other position to deliver hard water to the other end of the tank and drain it from the reverse end, ejector means associated therewith for drawing brine from a brine tank and delivering it to the softening tank, a brine tank, a float and float arm associated with said refill valve and brine valve, whereby said valves are controlled when the brine is flowing and when the tank is being refilled, the float unlocking the refill valve allowing it to close in its uppermost position and the float being adapted to open the brine valve when it is in its lowermost position.

6. In a water softener, a meter, means driven thereby for intermittently operating a needle valve, a needle valve, hydrostatic pressure admitted thereby to a hydraulic valve operating mechanism, a hydraulic valve operating mechanism, means connected therewith for rotating a rotary valve in one direction and yielding means connected therewith for moving the mechanism in another direction, a rotary valve having a casting, a rotary member with a plurality of ports and a flattened side whereby when it is in softening position the hard water will pass around one side of it to one end of the tank containing softening material out the other end of the tank to the center of the rotor and thence through the side of the rotor to service, while in the other position the hard water will be passed through the center of the rotor out the side thereof through an injector adapted to draw brine with it while a portion of the water will pass directly to service through the side of the rotor out one end, while the tank will be drained of its brine water by the brine passing from the tank at one end into the rotor casing alongside the rotor and thence out to a drain, and a drain.

7. In a water softening apparatus, a tank for softening material, a tank for regenerating material, a hard water inlet pipe connected to the softening tank, a service pipe connected to the other end of the softening tank, a pipe connecting the brine tank and the softening tank, a drain connected to the softening tank and a control mechanism for controlling the direction of the fluids during softening and regeneration consisting of a casing having a hard water inlet port, a port to service, a port to one end of the softening tank and a port to the drain, a

- 4
- port to the other end of the softening tank and a roller having a flat side for by-passing fluid through the rotor without passing the rotary, a port at the end of the rotary, ports 5 on the side of the rotor for communicating with either end of the tank and with the hard water line, a hard water line and an injector in the line leading to one end of the tank and the brine line connected therewith.
10. 8. In an automatic water softening apparatus, a softening tank, a brine tank having softening material and brine therein, a water meter, means actuated thereby to control a needle valve, a needle valve controlling hydrostatic pressure applied to hydrostatic valves, and a hydraulically operated valve operating mechanism, a stem therein moved in one direction by hydrostatic pressure and in the other direction by yielding means, a lever connected therewith at its free end, a rotary valve, a lever connected thereto adapted to be actuated by the last-mentioned lever, pipes leading from said rotary valve to the hard water supply, 25 to the bottom and top of the tank, to the drain, to the brine supply and to service, brine valves and refill valves in the brine line, a float for controlling the brine valve and a lock operated by said float for controlling the refill valve, said brine and refill valves being actuated in one direction by yielding means and in the other direction by hydrostatic pressure controlled by said needle valve.
30. 9. In an automatic softener, a meter, means driven by said meter for rotating a cam, a cam, means such as bell cranks operated by said cam for the control of a needle valve, a needle valve, means for conveying hydrostatic pressure from the main line through the needle valve to a plurality of hydrostatic valves and a hydrostatically operated valve operating mechanism, a hydrostatically operated valve operating mechanism adapted to operate a rotary valve for converting the softener from softening to regenerating position, and vice versa, and 35 a brine valve and a refill valve controlled by said hydrostatic pressure for controlling the admission of brine and the replenishment of water in the brine tank. 60
10. In combination in a softener, a softening tank, a brine tank, means for controlling the periods of regenerating and softening depending upon the amount of water passing through the system, a rotary valve, a needle valve, hydrostatic pressure controlled thereby, said needle valve being operated by said means depending upon the quantity of the water passing through the system, hydrostatic valves and a hydrostatically operated valve operating mechanism operated by said hydrostatic means, said hydrostatically operated valve operating mechanism being adapted to operate said rotary valve and 65 said hydrostatic valves being adapted to operate brine and refill valve, a brine tank, a brine line leading to the rotary valve, lines leading from the rotary valve to the top and bottom of the tank of softening material, a line leading from the rotary valve to service and a line leading from the rotary valve to drain, whereby in softening position the hard water passes to the bottom of the softening tank and out of the top to service 70 and in regenerating position the hard water passes to the top of the softening tank and out of the bottom to drain, drawing brine from the brine tank to the top of the softening tank and diverting a part of the hard 75 water direct to service.
11. In a water softener having a master rotary valve, a meter through which water passes under pressure, and means controlled thereby for operating said master rotary valve at predetermined intervals, of a hydrostatically operated plunger to which hydrostatic pressure is applied from the main supply of water under pressure at predetermined intervals determined by the controlling means which depends upon the quantity of fluid passing through the system. 85
- In testimony whereof, I affix my signature.
- CHARLES P. EISENHAUER. 90
